UNITED STATES PATENT OFFICE

2,516,798

MECHANICAL BARN CLEANER

Lester E. Peterson, Grantsburg, Wis.

Application February 24, 1948, Serial No. 10,491

2 Claims. (Cl. 198—218)

1

This invention relates generally to conveyors, and more particularly to a stable gutter cleaner comprising an elongated flexible carrier slidably mounted in the gutter of the stable, together with improved and simplified means for operating the carrier.

A primary object of this invention is to provide a stable gutter cleaner which will deliver material to a designated point outside of the stable with a minimum of labor and at minimum cost.

Another object of this invention is to provide carrier means for this purpose with properly arranged and proportioned reels and drums so that a maximum power is obtained for starting the carrier.

Still another object of this invention is to provide power driven reel means which may be enclosed within the barn or stable, with a relatively small portion of the mechanical apparatus used in this invention extending outside of the stable, with consequent increased convenience of the operator.

Yet another object of this invention is to provide a barn cleaner with an upwardly inclined extension of the gutter and providing an idler roll on the upper end of this extension, so that the drum on which the carrier is wound may be positioned underneath said extension; this positioning of the drum having been found to facilitate the installation, operation and maintenance of the cleaner.

Another object of this invention is to provide a flexible elongated carrier with two cables adapted to move the carrier in two directions when these cables are wound upon separate drums, this feature having been found to simplify the installation, operation and maintenance of these parts of the cleaner.

And the last object to be specifically mentioned is to provide a cleaner of the character described which is relatively inexpensive and practicable to manufacture, which is extremely simple, convenient and safe to operate, and which will give generally efficient and durable service.

With these objects definitely in view, together with other objects of a specific character which will become apparent as the description proceeds, this invention resides in certain novel features of construction, combination and arrangement of parts and portions as will be herein-after described in detail in the specification, particularly pointed out in the appended claims, and illustrated in the accompanying drawings which form a material part of this application, and in which:

2

Figure 1 is a horizontal sectional view of a stable having two gutters, each gutter having a cleaner constructed according to this invention operatively mounted therein and having separate controls incorporated with a single drive means;

Figure 2 is a vertical sectional view of the structure shown in Figure 1, the view being taken on the line 2—2 in Figure 1;

Figure 3 is an enlarged detail view, in top plan, showing the reels referred to herein-after as the power driven reels, together with the clutch means and control lever means therefor, the lever being shown in horizontal section and the other portions of the figure being shown in top plan;

Figure 4 is a vertical sectional view of a drive shaft and a clutch plate secured on this shaft, the view being taken on the line 4—4 in Figure 3, 20 and the clutch plate being shown in side elevation;

Figure 5 is a similar view showing the end of power driven reel adjacent to the clutch plate illustrated in Figure 4;

Figure 6 is an enlarged detail view, in vertical cross section, taken on the line 6—6 in Figure 3;

Figure 7 is an enlarged fragmentary detail view of the manual control means for the power driven reel;

Figure 8 is a side elevational view of the drum upon which the carrier is wound, together with the reel associated therewith;

Figure 9 is an enlarged plan view of the portion of the gutter and the adjacent portion of 35 the part herein-after referred to as the extension with the carrier therein, the view being designed to illustrate how angle iron guides are used to hold the adjacent portion of the carrier from being elevated when power is applied to the drum upon which the carrier is wound, portions of the wall of the stable being shown in horizontal cross section and the view being fragmentary in character;

Figure 10 is a fragmentary vertical longitudinal section, taken on the line 10—10 in Figure 11; and

Figure 11 is a transverse vertical sectional view, taken on the line 11—11 in Figure 9.

Similar characters of reference designate similar or identical parts and portions throughout the specification and throughout the several views of the drawings.

Referring now to the drawings in detail, the 55 environment wherewith this invention is adapted to be used includes a barn or stable having

walls 10 and 12, a roof or ceiling 14, a gutter 16, another gutter 18 which will ordinarily, but not necessarily be parallel to the gutter 16, and a complement of structure ordinarily associated with cattle barns and the like and including stanchions diagrammatically illustrated at 20.

A plurality of carriers and coacting mechanisms may be incorporated with a single drive means including an electric motor 22, a reduction gear box 24 and a long drive shaft 26, this specification being limited to a detailed description of a single carrier and the mechanism associated therewith, since the second carrier and mechanism are substantial duplicates of structure which will be described.

It is proposed to mount the drive shaft 26 in suitable bearings 28 bolted to the ceiling or roof 14, and the motor 22 and gear assembly may also be similarly mounted. A pair of reels 30 and 32, best illustrated in Figure 3, are freely rotatably mounted upon the drive shaft 26. The end plates 34 of these reels are of plain character but the outer end plates 36 are provided with a plurality of spurs or pins 38 adapted for selective engagement with correspondingly apertured clutch plates 40 which are rigidly secured to the drive shaft 26 by means of set screws 42 or other suitable means. That is, each clutch plate is provided with a plurality of apertures 44 adapted to receive the pins 38 on the end plate 36 of one of the reels 30 and 32 when these reels are moved together longitudinally of the drive shaft 26. A lever handle 46 is pivotally mounted on the loop 14, as at 48, and this handle carries a bifurcated member or yoke 50 having the arm portions thereof frictionally associated in grooves 52 formed in inwardly extending portions 54 of each of the reels 30 and 32. It will be seen that this clutch lever 46 may be used to move the reels longitudinally of the shaft 26 so that one or other of the clutch plates 40 will be engaged.

Cables 56 and 58 are terminally secured, one to each of the reels 30 and 32, and the cable 56 is entrained over pulleys 60 and 62 on the outside of the wall 10 which is suitably apertured, as at 64 and 66 to allow the cable to pass therethrough. The lower end of the cable 56 is secured by means of any suitable fastening means to what will be considered the inner end 68 of the carrier which is comprised of a pair of spaced apart parallel chains 70 and transverse slats or bars 72 terminally secured to these chains, the width of the carrier thus comprised being substantially equal to the width of the gutter 16, a practical amount of clearance being provided to allow the carrier to move easily along the gutter.

The other cable 58 is similarly associated with pulleys 74 and 76 mounted on the outside of the wall 12 and the outer end of the cable 58 is secured to the reel 78 which may be formed integral with the drum 80 upon which the outer end of the carrier is wound, and upon which the complete carrier is wound during the operation of the device. This drum 80 and the reel 78 are mounted on a shaft 82 which is, in turn, mounted upon an upright 84 incorporated with the extension 86, that is, the upwardly inclined table member disposed colinearly with the gutter 16 and extending outwardly from the wall 12 which is apertured, as at 88 to allow the carrier to pass therethrough. The exact construction of this extension 86 and the uprights 84 and 90 used to support the same is not thought material in this application, the essential feature being that the extension 86 shall be rigidly supported in proper

relation to the gutter 16 and that the upper outer end of the extension shall be constructed with suitable means, including a shaft 92 supported on any suitable bracket 94 and adapted to carry an idler roller 96 disposed transversely of the carrier which is entrained thereabout and returned for terminal securing to the drum 80. In this connection it may be noted that the end plate 98 and the center plate 100 of the drum 80 will be of considerable diameter and ruggedly constructed, and it is preferred that the transverse bars 72 on the carrier should be regularly spaced so that the diameter of the wound carrier on the drum 80 will be held to a minimum.

When an elevated extension 86 is used, tensioning of the carrier will tend to cause an intermediate portion thereof to rise out of the gutter 16, and a pair of angle iron guide members 102 on each side of the gutter and the extension 86 adjacent the wall 12 are provided to guide this portion of the carrier into the gutter 16. The ends of the guide members may be upturned as at 104.

The operation of this invention will be clearly understood from the foregoing description of the mechanical details thereof, taken in connection with the above recitation of the objects sought to be achieved by this invention.

In recapitulation, it need only be added that the handle 46 may be placed in neutral position or moved to cause the winding of either one of the cables 56 or 58 upon the respective reel, it being carefully noted that the said cables are wound in opposite directions upon these reels. This construction allows the motor 22, which will, of course, be supplied with proper power leads and switch connections, to be operated in one direction, a simplification over devices of a similar nature provided heretofore.

Material carried by the carrier over the idler roller 96 will fall by gravity from the carrier prior to the winding of this carrier upon the drum 80. Ordinarily, this material will be deposited in a manure spreader, or the extension 86 may be of such a height and character that the device may be operated for a considerable length of time without removal of the delivered material. As stated above, the operation of the second carrier is practically a duplication of the operation of the carrier described in detail, but it will be noted that the specific construction described above facilitates the incorporation of a plurality of carriers and operating mechanisms therefor with a single power unit such as the electric motor 22.

It will be clear from the foregoing that all of the objects of this invention have been amply achieved and it will also be clear that this invention may be embodied in structure varying in detail and proportionment of the parts thereof, all within the spirit and scope of the invention. Accordingly, this invention should be limited only in accordance with a proper interpretation of the terminology used in the subjoined claims.

Having described the invention, what is claimed as new is:

1. A stable gutter cleaner comprising an elongated flexible carrier slidably mounted in a gutter, a drum rotatively mounted colinearly with the gutter and beyond one end thereof, said drum being adapted to have said carrier wound thereon, an idler roller operatively associated with said carrier and disposed above and on the side of said drum remote from said one end of the gutter so that material transported by said carrier is gravitationally delivered from portions

of the carrier prior to the winding of said portions on the drum, means to rotate said drum and other means to retract said carrier into said gutter, said first mentioned means comprising a large diameter reel associated with said drum, a smaller diameter power driven reel, and a cable terminally secured to said reels, so that maximum power is obtained for starting the carrier, said other means comprising a power driven third reel, and a cable terminally secured to one end 5 of the carrier and to said third reel, said power driven reels being freely rotatively mounted on a drive shaft, motor means to drive said shaft in one direction, clutch means for selectively connecting said reels to said drive shaft, said cables being wound on said driven reels in opposite directions.

2. A cleaner according to claim 1 and including guide means for a carrier at the lower end 10 of said extension of the gutter comprising a pair of opposed angle iron members to engage the upper lateral edge portions of the carrier and to prevent the carrier from rising out of the gutter when being retracted.

5

6
of opposed angle iron members to engage the upper lateral edge portions of the carrier and to prevent the carrier from rising out of the gutter when being retracted.

LESTER E. PETERSON.
